UNITED STATES PATENT OFFICE.

GEORGE A. LONG, OF BOSTON, MASSACHUSETTS.

GRATE.

SPECIFICATION forming part of Letters Patent No. 634,694, dated October 10, 1899.

Application filed August 19, 1897. Serial No. 648,820. (No model.)

To all whom it may concern:

Be it known that I, GEORGE A. LONG, of Boston, in the county of Suffolk and State of Massachusetts, have invented an Improved 5 Grate, of which the following is a specification, reference being had to the accompanying drawings, in which—

Figure 1 is an elevation, partly broken away, showing my grate applied to the fire-box of a boiler. Fig. 2 is a plan of Fig. 1 with the boiler removed. Fig. 3 is a section on line 10 3 3 of Fig. 2, looking in the direction indicated by the arrow. Fig. 4 is a modified form of shaking device. Fig. 5 is a section on line 15 5 5 of Fig. 4, looking in the direction indicated by the arrow.

My invention is a conical grate supported at the bottom of a fire-box, with its apex extending upward and provided with means for 20 raising and lowering the grate bodily.

In the drawings, A is the grate, which is conical in form, the apex of the cone being cut off to make an opening for the split pipe a a', which guides the grate in its up-and-down 25 movement and serves as an axis on which it may be swung. The two sections a a' of this split pipe are fast to cross-pieces a² a³, which extend across underneath the fire-box and which are supported by dependent arms a⁴ a⁵, 30 which are fast to a ring a⁶, secured in the fire-box. The grate is supported in place by the cam or eccentric B, on which rests the cross-piece b' of ring b, which fits over split pipe a a', as clearly shown in Figs. 1 and 3. 35 The cam B is turned by means of arm b², which is journaled in the portion a a' of the split pipe and passes out at one side of the furnace. By turning the arm b² the grate may be raised and lowered bodily, as will be clear. 40 In Figs. 1 to 3 the grate is turned on its axis by means of arm D, fast to projection d on the under side of the grate.

In Figs. 4 and 5 I have shown a modified form of shaking and lowering device. In 45 these figures the arm b², fast to cam B, is inclosed in the hollow arm d', the end of arm b² extending beyond the end of arm d'. Fast to arm d' is arm d², extending upward and engaging projection d³, fast to the grate A.

The outer ends of arms b² and d' are preferably squared off to allow them to be grasped by a wrench. This modified form is especially adapted for use on parlor-stoves and the like, it making a more compact and a neater arrangement than the form shown in 55 Figs. 1 to 3.

It is obvious that that portion of the fire in contact with the walls of the furnace and with the grate will first die out—first, because the heat is radiated more quickly, and, secondly, 60 as to the grate, because combustion is fiercest at this point, as it is the place where oxygen is admitted. In some upright furnaces heretofore made when it has been desired to remove this waste matter it has been accomplished by shaking the entire body of fire, 65 with the result that in removing a part of the waste a very large portion of live coals would be removed, which subsequently would require to be sifted out of the pure ash and 70 clinkers. With my improved grate all this is changed. Nothing but waste matter is removed, so that no sifting of the contents of the ash-pit is required. The ashes being free to fall out around the walls, do so, while the 75 burned-out material close to the grate is also easily dislodged, leaving the center of the fire undisturbed and clear.

To operate my grate, the arm b² is first turned and the grate lowered as far as may 80 be necessary for the object in view. If the contents of the fire-box are to be dumped, the grate is lowered as far as it will go and a few shakes given by means of arm d, when the 85 object will be accomplished. If a mere removal of clogging ash and clinker is desired, the grate is lowered sufficiently to permit the clinkers to fall out and then raised to within one-half an inch of its topmost position, when it is turned by arm d until all ashes are 90 discharged.

What I claim as my invention is—

1. In combination grate A; ring b provided with cross-piece b'; split pipe a a' and cam B provided with arm b² all arranged and operating substantially as described. 95

2. In combination grate A provided with projection d³; split pipes a a'; ring b provided

with cross-piece b' ; cam B provided with arm b^2 and hollow arm d' provided with projection d^2 , all arranged to operate substantially as shown.

5. 3. In a furnace, the combination of a standard; a circular grate on the standard and free to turn about and slide upon the standard;

a cam supported by the standard and adapted by its rotation to raise the grate and a shaft to rotate the cam, substantially as described.

GEORGE A. LONG.
